UNITED STATES PATENT OFFICE.

SAMUEL RICHARD DAXON, OF PERRYTON, ILLINOIS.

MACHINE FOR MEASURING AND ELEVATING GRAIN.

SPECIFICATION forming part of Letters Patent No. 320,465, dated June 23, 1885.

Application filed March 12, 1885. (No model.)

To all whom it may concern:

Be it known that I, SAMUEL R. DAXON, a citizen of the United States, residing at Perryton, in the county of Mercer and State of Illinois, have invented a new and useful Improvement in Machines for Elevating and Measuring Grain, of which the following is a specification, reference being had to the accompanying drawings.

10 My invention relates to an improvement in machines for measuring, weighing, and elevating grain as it is discharged from a thrashing-machine; and it consists in the peculiar construction and combination of devices that 15 will be more fully set forth hereinafter, and particularly pointed out in the claims.

In the accompanying drawings, Figure 1 is a side elevation of a machine embodying my invention. Fig. 2 is a vertical longitudinal 20 sectional view of the same. Fig. 3 is a vertical transverse sectional view.

A represents a rectangular box, from the corners of which rise the vertical corner-posts B, which posts are connected by the horizontal longitudinal beams C, which extend above 25 the upper edges of the sides of the box.

D represents a rectangular frame, which fits in between the corner-posts B and rests normally on the beams C. The frame D is composed of the corner-posts d, the upper longitudinal beams, d', the lower longitudinal beams, d'', and the ends d'''.

On the under sides of the beams d'', at the centers thereof, is secured a horizontal transverse plate, d'', which is about equal in width to one-third the length of the frame D, and forms the bottom for a portion of said frame. Track-rails d''' are secured upon the upper sides of the beams d'', and upon these rails 35 40 slides the bottomless box E, which is divided into two compartments, e e', which are equal in size, being each about one-third the length of the frame D.

Side boards, F, connect the upper ends of 45 the corner-posts B, and these side boards are each provided with the horizontal slots f and the vertical slots f', which rise from the ends of the slots f. Transverse rods G project from the sides of the box E, at the 50 ends thereof, and enter the slots f.

A horizontal beam, H, is supported above

the machine, at a suitable height, by vertical posts h, and from this beam is suspended a scale-frame, I, which is fulcrumed, as at h', is hinged to a bail, e'', that is attached to the box 55 E, and has an outwardly-extending scale beam or lever, K, on which slides a balance-weight, L.

M represents a large chain-wheel, which is journaled on a spindle, m, that projects from one side of one of the beams d'', near one end thereof. A wrist-pin, m', projects from the outer side of this chain-wheel, the distance from the center of this pin to the center of the wheel being one-half the length of the compartments e e' and of the slots f. A pitman, N, is connected to the wrist-pin and to the projecting end of one of the rods G. When the wheel M is rotated, it follows that the box E will be moved back and forth in the frame 60 65 D. When the box E is at one end of the frame, one of its compartments will be over the plate d'', which serves as a bottom for it, while the other compartment will be over one end of the box A, and while the box E is at either 70 75 limit of its movement the rods G register with the vertical slots f', and the frame D is then free to rise.

O represents a transverse shaft, which is journaled in the box A. To one end of this 80 shaft is secured a miter-pinion, P, and to the opposite end is fixed a sprocket chain-wheel, R, and a pulley, S.

A sprocket chain-wheel, T, similar to the wheel R, is journaled at one end of the box 85 A, and is connected to the wheel R by an endless sprocket-chain, U. When the frame D is lowered, the wheel M meshes with the chain U, and, motion being imparted to the chain through the pulley S, is rotated thereby; but 90 when the frame D is raised the wheel M is out of contact with said chain.

The ends of the box A are inclined, as at a, and in the center of one side of the box is an opening, a', with which the lower end of an elevator-trough, V, communicates. In this trough is an endless elevator, of the usual construction, the lower roller of which has a miter-pinion, W, which meshes with the miter-pinion P.

The operation of my invention is as follows: The weight is set on the scale-beam at a suit-

able point to indicate the unit of measurement, and when the weight is so adjusted the frame D and the sliding box E are raised, and the wheel M is out of gear with the chain U. The 5 box E is at one end of the frame, with, say, the compartment e above the plate d'. The grain from the thrashing-machine is conducted through a spout, X, which is shown at Fig. 3, to the compartment e, and discharged there-
10 in. As soon as the grain which is discharged into the compartment e reaches the required weight, the frame D sinks, and the wheel M gears with the continually-moving chain U, which rotates the wheel and moves the box E
15 until the compartment e' is over the plate d'. and the contents of the compartment e have been dropped into the box A, when the frame D instantly rises, and the operation is repeated as before. The grain is raised from
20 the box A by the elevator in the trough V, and conducted to any suitable receptacle.

Having thus described my invention, I claim—

1. The combination of the reciprocating 25 bottomless box divided into compartments, the frame in which the box slides, said frame having a bottom or plate, which forms a bottom for each of the bottomless compartments successively, and a scale or balance to which 30 said frame is suspended, substantially as described.

2. The combination of the box A, having sides F, provided with the horizontal slots

f and vertical end slots, f', the frame D, having center plate or bottom, d', the sliding bottomless box E, divided into compartments and having projecting rods G, that extend into the slots f, the chain-wheel M, journaled to the frame D, pitman N, connecting said wheel and the sliding box, the scale or balance to 40 which the frame D is suspended, the sprocket-chain with which the wheel M gears, and actuating wheels for the chain, substantially as described.

3. The combination of the box A, having 45 sides F, provided with the horizontal slots f and vertical end slots, f', the frame D, having center plate or bottom, d', the sliding bottomless box E, divided into compartments, and having projecting rods G, that extend into the slots f, the chain-wheel M, journaled to the frame D, pitman N, connecting said wheel and the sliding box, the scale or balance to 50 which the frame D is suspended, the sprocket-chain with which the wheel M gears, actuating-wheels for the chain, and an elevator connected with the box A, and gears for actuating the elevator, substantially as described.

In testimony that I claim the foregoing as my own I have hereto affixed my signature in 55 presence of two witnesses.

SAMUEL RICHARD DAXON.
